FORM FOR NECKTIES

Harold M. Jarrett, Shinnston, W. Va.

Application August 24, 1951, Serial No. 243,423

1 Claim. (Cl. 2—153)

1

This invention relates to a form for neckties. More specifically, the invention comprises a form insertible in the knot of a four-in-hand necktie after the knot has been formed in the usual manner, to shape the knot and hold it securely against its normal tendency toward slippage.

One important object is to provide a device of the character described, that will permit the tie to be tied around the neck in the usual manner, and will permit the knot to be formed conventionally, so that the wearer need not apply the form until he has formed the knot in the manner to which he has been accustomed.

Another important object is to provide a form as stated that will be novelly designed to bind opposite faces of the form frictionally against the front necktie panel and the front portion of the knot, through the provision of a means specifically formed and arranged to counter the normal tendency toward relative slippage of these portions of a necktie.

Still another important object is to provide a device of the type stated wherein the means referred to above will not only be operative to prevent relative slippage between adjacent tie portions, but will also be effective to dimple the front panel of the necktie properly below the knot.

Still another important object is to provide a form of the character described that will be wholly invisible when the tie is being worn.

Another object is to provide a necktie form that will be capable of being readily manufactured at low cost, from a single piece of inexpensive material readily formed to the desired shape.

Other objects will appear from the following description, the claim appended thereto, and from the annexed drawing, in which like reference characters designate like parts throughout the several views, and wherein:

Figure 1 is a front elevational view of a necktie and collar as they appear when the form constituting the present invention is in use, said form being illustrated in dotted lines in proper position within the knot;

Figure 2 is a view similar to Figure 1 showing the form partially inserted;

Figure 3 is a perspective view of the form;

Figure 4 is an enlarged front elevational view, a portion of the form being broken away;

Figure 5 is an edge elevational view taken from the bottom of Figure 4; and

Figure 6 is a longitudinal sectional view, taken on line 6—6 of Figure 5.

2

Referring to the drawings in detail, a conventional shirt collar has been generally designated 10, and a conventional four-in-hand necktie is designated generally by the reference numeral 12.

5 The device constituting the present invention is readily stamped to shape from a single piece of metal material, or alternatively, can be moulded from plastic material or the like. In its completed form, the device includes a body generally designated 13 having a pair of body portions 14 each of which is approximately semi-circular in cross section. The body portions 14 are integrally joined along their inner side edges as at 16, so as to define a depressed medial portion extending longitudinally and centrally of the body. The longitudinally crimped or depressed portion cooperates with the transversely curved body portions to form the body with a plurality of side-by-side undulations disposed transversely of the body.

15 The body is formed to the general outer configuration of a conventional knot of a necktie, and to this end, the end edges 18 of the undulations or body portions 14 are straight and are disposed in longitudinal alignment, so as to be arranged parallel to and immediately above the bottom edge of the knot, as readily noted from Figure 1.

20 So as to impart to the knot the desired tapered shape, the outer side edges 20 of the body 13 diverge upwardly, along gradually curving lines, from the outer ends of the bottom edges 18.

25 Integral with the body 13, at the upper end thereof, are upwardly diverging wings 22, said wings being curved longitudinally thereof in a direction away from each other, to a slight extent, as particularly well shown in Figure 4.

30 The wings 22 are partially twisted in being extended away from the body 13, as may be noted by comparison of the plan view of Figure 4 with the edge elevational view of Figure 5. This is operative to engage one edge of each wing tightly against those portions of the necktie extending away from opposite sides of the knot to encircle the neck band of the collar 10.

35 Formed in the device, at opposite sides of the medial crimp or undulation 16, are upwardly diverging rows of openings 24, said rows extending longitudinally and substantially centrally of the undulations 14 and the wings 22 into which the respective undulations merge. The provision of these openings is effective to assist in preventing slippage of the knot, since the puncturing of the openings in the body and wings is operative to roughen the opposite faces thereof at the

edges of the openings, just sufficiently to coact with the frictional grip of the device upon the material of the tie, and thus aid in preventing slippage of the knot.

The knot of the necktie has been designated 26, and is formed in the conventional manner. In other words, the tie is applied to the collar 10 in the usual way, and the wearer ties the knot 26 in the accustomed manner. When the knot has been tied, the wearer pulls upon the lower edge 28 thereof to loosen the knot slightly, after which the device constituting the present invention is inserted downwardly into the knot, through the opening at the upper end thereof, in the manner shown in Figure 2.

The wings 22 are then slipped under the wings of the collar 10, as shown in either Figure 1 or 2, and the knot is then tightened.

Tightening of the knot will be effective to conceal the device completely, as shown in Figure 1, so that the device will be wholly invisible when being worn.

As will be noted, the device is so shaped as to form the knot to the desired taper, and after so forming the knot, the device acts to prevent slippage.

The slippage is prevented, in this connection, not only by the openings 24, but also, by formation of the body of the device with a plurality of side-by-side undulations, which in effect form the body into a spacer interposed between the front portion of the knot, and that part of the front necktie panel underlying the front knot portion. These undulations, in this connection, being extended longitudinally of the body, are arranged transversely to the direction in which the front portion of the knot would normally tend to slip. In other words, on slippage of a necktie knot, there is in effect a movement of the material of which the front knot portion is formed, transversely of the knot, that is, to the right or left when the knot is viewed as in Figure 1.

The undulations counter this tendency toward slippage of the knot, by binding opposite faces of the body 13 frictionally against the front necktie panel and the front portion of the knot respectively.

Further, the provision of the center crimp or undulation 16 has the further effect of forming a dimple 30 in the front necktie panel, immediately below the knot. The dimple 30, as may be noted from Figure 1, is properly and accurately formed, medially between opposite side edges of the necktie panel, and it is not possible for the wearer to dimple the necktie panel improperly.

It will be understood that the device can be formed of any suitable material, and by any process or manufacturing operation to which the shape of the device lends itself. In all instances, however, the device has the important characteristics of being capable of being fabricated from inexpensive material, and by simple manufacturing operations.

As will be noted from Figure 1, the outer edges of the wings 22 are formed as extensions of the upwardly diverging outer edges of the body portions, with the inner edges of the wings converging in the direction of the body to meet at the upper end of the medially disposed depressed portion of the body. This arrangement of the inner edges causes said inner edges to cooperate to define a V-shaped recess at the upper end of the body, the recessed upper end edge of the body

thus being wholly concealed within a previously formed tie knot having the usual, substantially horizontally extended top edge.

It is believed clear that the invention is not necessarily confined to the specific use or uses thereof described above, since it may be utilized for any purpose to which it may be suited. Nor is the invention to be necessarily limited to the specific construction illustrated and described, since such construction is only intended to be illustrative of the principles of operation and the means presently devised to carry out said principles, it being considered that the invention comprehends any minor changes in construction that may be permitted within the scope of the appended claim.

What is claimed is:

A device for preventing knot slippage in a necktie, comprising: a body formed with a pair of generally vertical, side by side body portions of approximately semi-circular cross section integrally joined along their inner side edges to define a depressed, tie-dimpling medial portion extending longitudinally and centrally of the body, said depressed portion cooperating with the body portions to form the body with a plurality of side by side undulations disposed transversely of the body, the body portions being formed at their lower ends with straight end edges disposed in longitudinal alignment so as to extend parallel to and immediately above the bottom edge of a tie knot, the outer side edges of the body diverging upwardly along gradually curving lines from the outer ends of said lower end edges; and upwardly diverging wings integral with the body at the upper end thereof, said wings being curved longitudinally in a direction away from each other and being partially twisted to engage one edge of each wing against those portions of the tie extending from opposite sides of the knot, said wings and body portions having their opposite faces roughened throughout their lengths to frictionally grip the material of the tie, the outer edges of the wings being formed as longitudinal extensions of the upwardly diverging outer edges of the body portions and the inner edges of the wings converging in the direction of the body to meet at the upper end of the depressed medial portion, said convergent inner edges of the wings defining a substantially V-shaped upper end edge on the body, for recessing of the upper end of the body wholly within the knot, below the substantially horizontally extending top edge of said knot.
